UNITED STATES PATENT OFFICE.

CLARENCE R. WELCH, OF DENVER, COLORADO.

HOISTING-ENGINE CONTROLLER.

Application filed January 2, 1924. Serial No. 683,940.

To all whom it may concern:

Be it known that I, CLARENCE R. WELCH, a citizen of the United States, residing at Denver, in the city and county of Denver 5 and State of Colorado, have invented certain new and useful Improvements in Hoisting-Engine Controllers; and I do declare the following to be a full, clear, and exact description of the invention, such as will enable others skilled in the art to which it appertains to make and use the same, reference being had to the accompanying drawings, and to the characters of reference marked thereon, which form a part of this specification. 10

This invention relates to improvements in hoisting engine controllers.

In mines of all kinds where material and men must be hoisted from various distances 20 underground, it is essential to safety that the action of the hoist shall be controlled so that it will not exceed certain predetermined limits, nor travel too far in either direction. It is also essential that the speed of the hoist 25 shall be decreased when it reaches a position of from 50 to 100 feet of the top or the bottom so that it can safely be brought to a full stop. Where a hoist is used for handling both men and material, it is essential 30 that it shall be operated at a lower speed when the men are raised and lowered than when inert material is handled. In addition to the above, it is the object of the present invention to improve the construction and 35 operation of controllers of this general type that have heretofore been invented by me and for which I have already received Letters Patent.

In order to better and more clearly describe my invention, I shall have reference to the accompanying drawing in which the preferred embodiment is shown, and in which:

Fig. 1 is a side elevation of my controller showing the same inoperative;

Fig. 2 is a fragmentary view similar to that shown in Fig. 1, but with parts broken away to better show the construction;

Fig. 3 is a section taken on line 3—3, Fig. 2;

Fig. 4 is an elevation showing the reverse side from that shown in Fig. 1 with the cover removed from the casing and with other parts broken away;

Fig. 5 is a section through the centrifugal governor;

Fig. 6 is an elevation similar to that shown

in Fig. 1, but with parts removed to more clearly disclose the operation;

Fig. 7 is a section taken on line 7—7, 60 Fig. 6; and

Fig. 8 is a diagrammatic representation of the various parts.

The same reference characters will be used to designate the same parts throughout the several views. 65

Numeral 1 represents a casing within which some parts of the machinery are housed and which is provided about its base with outwardly extending flanges 2, by means of which the housing may be connected to the corresponding flange 3 on the support 4. Extending through the housing and rotatably mounted in bearings 5 and 6 is a shaft 7 that has secured to one end a sprocket wheel 8. A worm 9 is secured to the shaft between the bearings 5 and 6 and this is operatively related to the worm gear 10 which is non-rotatably secured to the shaft 11, which extends through the casing and has the wheel 12 secured to the outer 70 end thereof. Shaft 7 extends outwardly through the casing and has slidably but non-rotatably connected thereto a double gear 13. Mounted parallel to the shaft 7 is a shaft 14 to one end of which is connected 75 the gears 15 and 16, which are of different sizes and are so related to the double gear 13 that the latter can cooperate with either. The double gear has a collar 17 which is provided with an annular groove that is 80 engaged by pin 18 on the end of the arm 19, which in turn is pivotally connected at 85 20 to the projecting arm of the bracket 21. Arm 19 is welded or otherwise secured to the lever 22, to the outer end of which the weight 23 is adjustably secured. The inner end of lever 22 is connected by suitable links 123 with the core 24 of the solenoid 25. When the parts are in the position shown in 90 Fig. 4, the shaft 14 is rotated at what may be termed "low speed," but when the solenoid 25 is energized, it tilts lever 22 about its pivot in a counter-clockwise direction 95 and causes the larger of the double gears to mesh with the gear 15, thus increasing the gear ratio and causing the shaft to rotate at a higher speed relative to the shaft 7. To the inner end of the shaft 7 I secure a bevel gear 26, which cooperates with a 100 similar gear 27 on the tubular shaft 28, within which is slidably mounted the rod 29. The tubular shaft 28 extends through

a bearing 30 which has an outwardly extending flange 31 by means of which it is secured to the upper surface of the casing in the manner shown in Fig. 5. The upper 5 and the lower ends of the bearing 30 are provided with raceways for the balls 32, while collars 33 and 34 are clamped to the hollow shaft and are also provided with raceways; all as shown in Fig. 5. The upper 10 end of tubular shaft 28 has an enlarged portion 35 for the reception of the enlarged end 36 of rod 29, which is provided with gear teeth 37. Pivoted to the outwardly projecting lugs 38 are the governor arms 39 15 whose upper ends are provided with gear teeth 40 that cooperate with the teeth 37. A cap 41 closes the opening in the upper end of the enlarged portion 35.

From the above it is apparent that by 20 rotating the shaft 7, the tubular shaft 28 will also be rotated, thereby rotating the governor, the arms of which will move upwardly and outwardly, thereby forcing the rod 29 downwardly. The lower end of rod 25 29 rests upon the abutment 42 (Fig. 7) on the end of lever 43, which is pivoted at 44 and carries a roller 45 at its outer end. When the speed of the device increases, the 30 governor arms move upwardly, thereby 30 moving the rod 29 downwardly and the roller 45 upwardly, thereby effecting a control that will be hereinafter described.

The sprocket wheel 8 is connected to the hoist drum or other parts that rotate at the 35 same speed as the drum and therefore the shaft 7 will rotate at a speed proportional to the speed of the hoist. Since the wheel 12 is connected to worm wheel 10 that is driven directly from shaft 7 through the 40 medium of the worm 9, it rotates at an angular velocity that is proportional to the speed of the hoist. The gears and driving parts are so proportioned that the wheel 12 will rotate less than 360 degrees for the 45 entire travel of the hoist so that it will never make a complete revolution. The reason for this will presently appear.

Referring now particularly to Fig. 6, it 50 will be noted that an arm 46 is supported from shaft 11 by means of a collar 47. To the lower end of arm 46 I slidably secure a weight 48, and to this is connected an arcuate segment 49. The upper or concave side of this segment is provided with ratchet teeth. In the drawing I have shown 8 teeth 55 on each side of the arm. The four teeth nearest the center are curved on a shorter radius of curvature than the four outer teeth, in the manner most clearly shown in Fig. 1. Above the weight 48 I secure to the arm 46 three weights 50, 51 and 52, each 60 of which is slidable on the arm and is normally supported by a pin 53. Secured to the upper side of weight 48 and projecting 65 upwardly therefrom, one on each side of the

arm 46 are pins 54, which are adapted to engage the lower side of the weight 50 and raise the same against the action of gravity in the manner shown in Fig. 6. The lower 70 surface of the arcuate member 49 is circular and lies directly over the roller 45, consequently the roller will contact with and raise the arcuate member when the speed is great enough to permit the governor to tilt the lever 43 sufficiently to accomplish this.

As 75 a matter of fact, whenever the controller is operating, even at very low speeds, the arcuate member 49 rests on the roller 45 and its distance from the periphery of wheel 12 depends upon the position of the governor 80 arms 39. If the governor had a constant weight against which to act the arcuate member 49 would move upwardly more or less in accordance with the speed, but as it moves upwardly the ends of rods 54 will engage the weight 50, which will increase the 85 resistance against which the governor must work. Therefore, the member 49 will remain stationary until the speed has increased sufficiently to enable the governor 90 to lift weight 50.

Then there will be a gradual upward movement of the arcuate segment 49 until weight 51 engages weight 52, when the parts will remain stationary 95 until the speed increases sufficiently to raise this weight also. It will be seen from the above description that if the governor is subjected to a gradual constant increase in speed, the arcuate segment 49 will not rise at all times at a rate proportional to the increase in speed, but that it will remain stationary for a short period whenever one or the other of the three weights 50, 51 and 52 are added to the mass of weight 48. In like 100 manner, when there is a negative acceleration or slowing down of the speed, the governor will fall gradually for awhile and then stop until the speed has diminished sufficiently to overcome the reduction in resistance due to the fact that weight 52 is 105 removed from effective participation and rests upon a pin 53. There will then be a gradual lowering of the segment 49 and the governor arms until weight 51 reaches and rests upon its supporting pin 53, when the parts will remain stationary until the speed 110 has decreased so as to compensate for the removal of the weight. This step by step raising and lowering of the segment 49 is of great importance, as it increases the speed 115 of operation of the controller by preventing the governor arms from sinking too far down, which would mean that if the speed should start increasing, more time would be required for the parts to reach operative 120 position.

The wheel 12 is provided with a plurality of notches 55 on its outer periphery and a plurality of holes 56, which extend through the outer rim. Pawls 57 are pivoted at 58 to 125

lugs 59, which are secured to the wheel rim by screws 60, which cooperate with the holes 56. These pawls are so located on the wheel that they will engage one or the other of the 5 shoulders 61, when the hoist approaches near to the limit of its travel, whereby any further movement will move arm 46 out of vertical position to a position somewhat like that shown in Fig. 6. The pawls 57 will 10 scarcely ever engage the shoulders 61, as this can only happen if the speed of the hoist is so low that the governor is substantially inactive. If the hoist is running at ordinary speed, the pawls will engage the teeth near 15 the end and if the speed is so low that the pawls do not engage the teeth near the end, they will catch the teeth near the center, which project closer to the wheel 12. As the hoist approaches the end of its travel, it will 20 be necessary for the engineer to slow down gradually so that the toothed segment will move downwardly a sufficient distance to prevent the pawls 57 from engaging the same. The arcuate segment 49 carries a pin 25 62 (Figs. 1 and 2), which is adapted to engage with any one of the teeth 55 and will so engage on excessive speeds. In Fig. 6 I have shown a mechanism which tends to hold the arm 46 in vertical position. This 30 consists of a member 63 projecting from the side of the ring 47. This member has a triangular notch 64 which cooperates with a spring-pressed plunger 65. The reaction between plunger 65 and the sides of the notch 35 64 tends to maintain the parts in such a position that the rod 46 is vertical. An arm 66 is secured to the ring 47 and has its upper end lying over the block of insulating material 67, upon which are secured electrical contacts 68, 69 and 70. To the arm 46 I secure an insulating member 71 which carries two spaced electrical contacts 72 and 73. To weight 52 I secure a contact 74 which is adapted to engage and electrically connect 40 members 72 and 73 when weight 52 is resting on its supporting pin 53. On the weight 52 I secure an insulating member 75, to which is attached a contact 76 that is adapted to engage weight 51, when the latter is 45 raised from its supporting pin 53. This forms a switch which closes an alarm circuit whenever the weight 51 is raised a sufficient distance to make connection with the contact 76. The object of this will be hereinafter 50 explained.

Referring now more particularly to Fig. 8, numerals 77 and 78 are two electromagnets which are preferably connected in multiple and fed from a source 78' of electrical energy. A lever 79 is pivoted at 80 to a supporting bracket 81. An armature 82 is connected to one end of said lever and cooperates with the magnet 78. To the other end of the lever there is secured a weight 83, which tends to rotate the lever in a clockwise direction about its pivot. A dash pot 84 is connected to the lever and this is provided with a by-pass 85 connecting the chambers on both sides of the piston 86. The opening through the by-pass is controlled by a valve 87 which is operated by the lever 88. This lever has an armature 89 which cooperates with the magnet 77. To the free end of the lever 88 a weight 90 is connected. This weight tends to move the lever clockwise and partially close the valve 87, but is normally restrained by the action of the magnet 77. A rod 91 is connected to the lever 79 and to the brake of the hoist, as well as to the throttle valve in such a manner that when the magnet 78 is de-energized, the weight 83, acting through the lever 79 and rod 91, will cut off the power and apply the brake, thereby stopping the hoist. When the lever 88 is in the position shown in Fig. 8, valve 87 is wide open and the brake is applied quite suddenly, but if magnet 77 is de-energized as well as magnet 78, then the brake will be more gradually applied. It is my object to stop the hoist under the following conditions.

(a) When the hoist has reached the extreme limit of its travel; (b) if a dangerous speed is attained between landings; (c) if the speed is not sufficiently reduced when the hoist approaches within 100 feet or so of the extreme limit of its travel; and (d) if for any reason an emergency should require the machinery to be stopped suddenly.

That portion of the travel of the hoist which lies within 50 to 100 feet of the extreme limit of its travel, is subject to the overspeed and emergency control only. The over speed control, as above explained, operates through the governor which lifts the several weights in seriatim. As long as the speed is sufficient to raise the weight 50, only then nothing happens, but when the speed increases until weight 51 is moved upwardly a sufficient distance to cause it to come into electrical contact with spring 76, the circuit to the alarm 93 is closed. This calls the attention of the engineer to the fact that the speed is approaching the danger point. If the speed increases sufficiently to cause weight 52 to be moved upwardly some distance, the contact 74 will disconnect contacts 72 and 73, thereby de-energizing both electromagnets. Armature 82 will be released and the weight 83 will rotate the lever 79 about its pivot 80. Armature 89 will also be released, thereby causing valve 87 to be partially closed so as to increase the retarding effect of the dash-pot 84. The idea is to apply the brakes gradually when the controller is caused to operate through the overspeed control. If any one of the switches 94, of which there may be any number, located at strategic points, are opened, the electromagnet 78 will be de-

energized, thereby releasing the armature 82 and the brakes will be suddenly applied. Since magnet 77 is not de-energized, except by the overspeed control, the dash pot will 5 operate with the by-pass wide open, and the action of the controller in cutting off the power and applying the brakes will be almost instantaneous.

Should the engineer neglect to decrease 10 the speed when the hoist approaches the danger zone, then one or the other of pawls 57 will engage a tooth on the arcuate segment 49 in the manner shown in Fig. 6, and move the rod 46 from vertical position. 15 This moves the contact arm 66 and as soon as this becomes disconnected from contact 69, the electromagnet 78 will be de-energized, bringing the hoist to a sudden stop. It will be noted that the ratchet teeth on the 20 arcuate member 49 are slightly higher toward the center. This requires the engineer to gradually decrease the speed toward the end of the hoist travel. If the engineer should neglect to stop the hoist when it 25 reaches the end of its travel, one or the other of pawls 57 will engage one of the shoulders 61 and move the contact arm 66 out of electrical contact with 69, thereby causing the stop mechanism to operate by 30 de-energizing the magnet 78.

When the hoist is to be used for handling men, it is necessary to operate it at a much slower speed. In order to change the adjustments of the controller so that it will 35 become operative at lower hoist speed, I change the gear ratio between shafts 7 and 14. This is accomplished by moving the double gear 13 so that the larger gear will operate with the gear 15 on the shaft 14. 40 This causes the governor to rotate faster with the same speed of the hoist and consequently it will cause the controller to become active at much lower hoist speed. The gear 13 is preferably shifted by electrically 45 operated means, such as the electromagnet 25, which is connected to a source of electrical energy 95 and is controlled by a normally open switch 96. A signal lamp 97 is located at some point in the shaft and will 50 be illuminated whenever the magnet 25 is energized.

Should the engineer start the hoist while 55 loaded with men without first energizing magnet 25, the men, noticing that the lamp 97 was dark, could stop the hoist by merely opening one of the circuit closers 94, which may be located on the hoist for this purpose.

I want to call particular attention to the 60 fact that I have provided a plurality of weights 50, 51 and 52, which are normally free from the governor, but which are added to the resistance against which the governor operates as the speed increases. This permits the governor arms 39 to raise 65 to a considerable height, even at compara-

tively low speed so that if a sudden emergency arises they will be in position to respond quickly. The governor's construction is such that if it is subjected to a uniform acceleration, it will move in successive steps, due to the fact that the resistance against which it operates is not constant or increased uniformly, but by separate steps.

From the above it will be evident that I 75 have produced an improved hoisting engine controller that (a) can be made operative by merely pressing a button, of which there may be several located at various points; that (b) will stop the hoist almost instantaneously whenever an emergency arises, when the end of the travel is reached or if the engineer neglects to reduce the speed when the hoist approaches near the end of its travel; and (c) which will stop the hoist 80 at any part of its travel if the speed is too great.

Having now described my invention, what I claim as new is:

1. A controller for hoisting engines having a drum, comprising, in combination, a centrifugal governor, means for rotating the governor at a speed proportional to the speed of the drum, means for stopping the drum, said last named means comprising a mechanism for cutting off the power and for applying a brake to the drum, means comprising an electromagnet for holding the stopping means inoperative, means for de-energizing said electromagnet whenever the speed of the drum exceeds a predetermined amount, said de-energizing means comprising a switch connected to the energizing circuit of the electromagnet, and means cooperating with the governor for operating said switch and de-energizing said electromagnet when the speed exceeds a predetermined value, said governor having resistance means which is applied in steps whereby the governor acts intermittently when subjected to a constant rotary acceleration.

2. A controller for hoisting engines having a drum, a centrifugal governor, means for rotating the governor at a speed proportional to the speed of the drum, means for stopping the drum, said last-named means comprising a mechanism for cutting off the power and for applying a brake to the drum, means comprising an electromagnet for holding the stopping means inoperative, means for deenergizing said electromagnet whenever the speed of the drum exceeds a predetermined amount, said last-named means comprising a switch connected to the energizing circuit of the electromagnet, means cooperating with the governor for operating said switch and de-energizing said electromagnet when the speed exceeds a predetermined value, said governor having resistance means which is applied in 120 steps whereby the governor acts intermittently when subjected to a constant rotary acceleration.

steps whereby the governor acts intermittently when subjected to a constant rotary acceleration, means for causing said stopping means to become operative at a lower speed 5 towards the ends of the hoist travel, said means comprising a pendulum, and means for normally holding the same in vertical position.

3. A controller for hoisting engines having a drum, comprising in combination, a centrifugal governor, means for rotating the governor at a speed proportional to the speed of the drum, means for stopping the drum, said last named means comprising a mechanism 10 for cutting off the power and for applying a brake to the drum, means comprising an electromagnet for holding the stopping means inoperative, means for de-energizing said electromagnet whenever the speed of the drum exceeds a predetermined amount, said de-energizing means comprising a switch connected to the energizing circuit of the electromagnet, means cooperating with the governor for operating said switch 15 and de-energizing said electromagnet when the speed exceeds a predetermined value, said governor having resistance means which is applied in steps whereby the governor acts intermittently when subjected to a constant rotary acceleration, and means comprising a pendulum for causing said stopping means to become operative at a lower speed 20 towards the ends of the hoist travel, means for normally holding the pendulum in vertical position, a pawl mounted to rotate about a central pivot at a speed proportional to the speed of the hoist, an arcuate toothed segment secured to the pendulum and slidable thereon, means 25 operable by the governor for moving said segment toward or away from the locus of the pawl, and a switching device operable by the pendulum as it moves from its vertical position, said switching device being 30 adapted to de-energize the electromagnet.

4. A controller for hoisting engines having a drum, comprising, in combination, a centrifugal governor, means for rotating the governor at a speed proportional to the speed 35 of the drum, means for stopping the drum, said last named means comprising a mechanism for cutting off the power and for applying a brake to the drum, means comprising an electromagnet for holding the stopping means inoperative, means for de-energizing said electromagnet whenever the speed of the drum exceeds a predetermined amount, said de-energizing means comprising a switch

connected to the energizing circuit of the electromagnet, means for retarding the action of the stopping mechanism, said retarding means comprising a dash pot provided with a by-pass, a valve in said by-pass, means comprising an electromagnet for retaining said valve in fully open position, means tending to move the valve to partially closed position when the last-named electromagnet is de-energized, means for de-energizing the first-mentioned electromagnet when the hoist reaches the limit of its travel, means for de-energizing the first-mentioned electromagnet when the hoist approaches the limit of its travel at too great a speed, and means for de-energizing both of said electromagnets when the speed of the drum exceeds a maximum.

5. A controller for hoisting engines having a drum, comprising in combination, a centrifugal governor, means for rotating the governor at a speed proportional to the speed of the drum, means for stopping the drum, said last named means comprising a mechanism for cutting off the power and for applying a brake to the drum, means comprising an electromagnet for holding the stopping means inoperative, means for de-energizing said electromagnet whenever the speed of the drum exceeds a predetermined amount, said de-energizing means comprising a switch connected to the energizing circuit of the electromagnet, means for retarding the action of the stopping mechanism, said retarding means comprising a dash pot provided with a by-pass, a valve in said by-pass, means comprising an electromagnet for retaining said valve in fully open position, means tending to move the valve to partially closed position when the last-named electromagnet is de-energized, means for de-energizing the first-mentioned electromagnet when the hoist reaches the limit of its travel, means for de-energizing the first-mentioned electromagnet when the hoist approaches the limit of its travel at too great a speed, means for de-energizing both of said electromagnets when the speed of the drum exceeds a maximum, 100 said last named means comprising the centrifugal governor, and means comprising a plurality of weights that are added in seriatim to the governor whereby it will operate in a series of steps when subjected to a uniform acceleration.

In testimony whereof I affix my signature.

CLARENCE R. WELCH.
